CLAIM

The ornamental design for a putter head, as shown and described.

DESCRIPTION

FIG. 1 is a front elevation view of a putter head;

FIG. 2 is a rear elevation view thereof;

FIG. 3 is a top plan view thereof;

FIG. 4 is a bottom plan view thereof;

FIG. 5 is a heel-side elevation view thereof; and,

FIG. 6 is a toe-side elevation view thereof.

The broken lines shown in the drawings form no part of the claimed design.
